UNITED STATES PATENT OFFICE.

JOHN B. ROOT, OF PORT CHESTER, NEW YORK.

MACHINE FOR RIVETING SHEET-METAL PIPE.

SPECIFICATION forming part of Letters Patent No. 292,364, dated January 22, 1884.

Application filed September 10, 1883. (No model.)

To all whom it may concern:

Be it known that I, JOHN B. ROOT, of Port Chester, in the county of Westchester and State of New York, have invented certain new and 5 useful Improvements in Machines for Riveting Sheet-Metal Pipe; and I hereby declare the same in the following full, clear, and exact description thereof.

The improved features relate to machines for 10 riveting punched sheet-metal blanks, particularly those designed for pipe-sections and various other tubular articles, the machine herein described being especially adapted to riveting the blanks from which house or range boilers are made. These features consist, in combination with a riveting-mandrel, of a rivet-carrier for conveying the rivets from a rivet-tube or other suitable rivet-feeding device, arranged to deliver the rivets to the machine at 15 a point without the position the blank to be operated upon may take, along or within the mandrel to the point where they are to be inserted in the blank, and then headed down; and, further, in a spring or other yielding catch 20 arranged to retain the rivets in the forward position to which they are conveyed by the carrier, and in a reciprocating plunger arranged so as to force the rivets up through the blank from such forward position or into the 25 holes punched therein.

In the accompanying drawings, Figure 1 is a side elevation of the machine, with the mandrel in central section. Fig. 2 is a top or plan view of the machine. Fig. 3 is an end view 30 of the mandrel. Fig. 4 is an elevation of a modified smaller machine; and Figs. 5, 6, 7, 8, and 9 are enlarged detail views of the rivet-retaining catch, rivet-carrier, and rivet-tube.

In these views, the letter A represents the 35 bed of the machine, and B a standard rising therefrom, which supports the mandrel C and associated riveting mechanism.

D is a rivet-carrier which lies in a groove 40 running along the top of the mandrel. It is provided with a rack, E, which engages with a gear F, and is of sufficient length so that by the revolution of this gear the forward forked end, G, of the carrier, Fig. 8, is reciprocated from a point behind the rivet-tube H 45 to the head of the mandrel or anvil I. The gear F is provided with a pinion, J, which engages with a rack, K, connected by pitman L

to the treadle M, the operation of which, it will be seen, advances the rivet-carrier, the weight of the parts being sufficient to return it. In 55 thus advancing, the forked end of the carrier engages the shank of a rivet which has fallen from the rivet-tube into the carrier-groove, as seen in Fig. 9, and conveys it to the riveting end of the mandrel, the lower end of the rivet-tube being closed by the carrier, and the rivets thereby prevented from escaping until the carrier is returned. As a rivet reaches the anvil I it passes by a catch, N, which is made yielding by spring O to the advance of the rivet, 60 and is shaped to engage the head of, and thereby retain, the rivet when the carrier recedes.

P is a plunger, which is reciprocated by lever Q, supported in a groove in the under side of the mandrel, and connected with the operating-treadle R by pitman S, and the location and arrangement of this plunger are such that the rivet-carrier leaves the rivets resting upon the end thereof, as seen in Fig. 5. It will now be plain that, upon bringing one of the holes of a pipe or other blank over the position of the rivet and depressing the treadle R, the rivet upon the end of the plunger will be forced into the blank, as seen in Fig. 6. The blank is then shifted slightly to one side and the rivet 75 headed down either by hand or suitable auxiliary heading mechanism, and in thus shifting the blank another hole may be brought into position to receive a rivet, as shown in Fig. 6. The right adjustment of the blank, when shifting it to head a rivet, so as to also bring an unfilled hole accurately over the rivet-inserting plunger, is conveniently effected by bringing the head of the rivet last inserted into a shallow indent, T, for longitudinal seams, or 80 into an indent, U, for circular seams, these indents being located the same distance from the axis of the plunger as is that between the corresponding punched holes of the blank.

In Fig. 4 I show a modified form of this machine as adapted for riveting smaller blanks than the machine of the first two figures. Here, in order to preserve proper strength of the mandrel, a sliding wedge, V, operated by an arm, W, rising from the treadle R, is used to 95 reciprocate the rivet-inserting plunger.

It is preferred that the operating-treadles of the machine be properly weighted, either by their connections or by an added weight, as

shown, upon the rivet-inserting treadle, so that the backward movement of the parts may be effected automatically. These treadles may, however, be dispensed with and the operation made wholly automatic by suitable connections with some source of power.

It is plain that other means for connecting the rivet-carrier with the operating-wheel than by a rack and gearing may be employed, and 10 I do not, accordingly, confine myself to the precise construction shown. So, also, though I have spoken of the blank as being punched, it is manifest that this is not essential, for the rivet-inserting plunger may be employed to 15 force the rivets through an unpunched blank; and this plunger, too, may be employed in lieu of an anvil, and the rivets be headed upon it, it being arranged to withstand the heading mechanism.

20 What is claimed as new is—

1. In a pipe-riveting machine, the combination of a riveting-mandrel with a sliding rivet-carrier contained therein, and adapted to reciprocate from one end thereof to the 25 other or riveting end, for the purpose set forth.

2. In a pipe-riveting machine, the combination of a riveting-mandrel with a sliding rivet-carrier contained therein, and gearing for reciprocating such rack, as and 30 for the purpose set forth.

3. In a pipe-riveting machine, the combination of a riveting-mandrel, a longitudinally-

moving rivet-carrier contained therein, and a yielding catch arranged to retain the rivets as the carrier returns from its forward movement, 35 for the purpose set forth.

4. In a pipe-riveting machine, the combination of a riveting-mandrel, a rivet-carrier arranged to convey the rivets to the riveting end of the mandrel, and a reciprocating plunger arranged to insert the rivets in the blank, 40 as set forth.

5. The combination, in a pipe-riveting machine, of a riveting-mandrel, a rivet-feeding device located without the position of the blank 45 operated upon, and a rivet-carrier reciprocating in the mandrel, and adapted to carry the rivets from the rivet-feeding device to the riveting end of the mandrel, substantially as set forth.

6. The combination, in the machine herein described, of the mandrel, the rivet-carrier and its reciprocating gear, the connecting-rack and pitman, and the operating-treadle, substantially as set forth.

7. The combination, in the machine herein described, of the mandrel, the rivet inserting plunger, its reciprocating levers, and the operating-treadle, substantially as and for the purpose set forth.

JOHN B. ROOT.
